CLAIM

The ornamental design for a ring with internal stones, as shown and described.

DESCRIPTION

FIG. 1 is a top plan view of a ring with internal stones showing my new design;

FIG. 2 is a front elevational view thereof, the opposing side being a mirror image thereof;

FIG. 3 is a right side perspective view thereof;

FIG. 4 is a left side perspective view thereof; and,

FIG. 5 is a top perspective thereof.

The broken lines shown in the drawings illustrate portions of the ring with internal stones that form no part of the claimed design.
